UNITED STATES PATENT OFFICE

91,263

DESIGN FOR A TURRET SUPPORT FOR LUBRICATING APPARATUS

Frank S. Barks, St. Louis, Mo., assignor to
Lincoln Engineering Company, St. Louis, Mo.,
a corporation of Missouri

Application April 17, 1933. Serial No. 47,809

Term of patent 3½ years

To all whom it may concern:

Be it known that I, FRANK S. BARKS, a citizen of the United States and a resident of St. Louis, Missouri, have invented a new, original, and ornamental Design for a Turret Support for Lubricating Apparatus, of which the following is a specification, reference being had to the accompanying drawing, forming part hereof, in which

Fig. 1 is a plan view of a turret support for lubricating apparatus showing my new design.

Fig. 2 is a side elevation of Fig. 1.

I claim:

The ornamental design for a turret support for lubricating apparatus, substantially as shown.

In testimony whereof, I have signed my name to this specification this 11th day of April, 1933.

FRANK S. BARKS.
